**COMBINED LIGHT SUPPORT AND FILTER AC-
TUATING ACCESSORY BRACKET FOR A PHO-
TOGRAPHIC CAMERA**

Jack A. Robinson, Chicago, Ill., assignor to Acme-Lite
Manufacturing Co., Inc., Chicago, Ill., a corporation
of Illinois

Filed Aug. 27, 1965, Ser. No. 86,752

Term of patent 14 years

(Cl. D61—1)

FIG. 2

FIG. 1

FIG. 4

FIG. 5

FIG. 6

FIG. 1 is a front elevational view of a combined light support and filter actuating accessory bracket for a photographic camera showing my new design;

FIG. 2 is a rear elevational view thereof;

FIG. 3 is a top view thereof;

FIG. 4 is a bottom view thereof;

FIG. 5 is a side elevational view; and

FIG. 6 is an elevational view of the side opposite that seen in FIG. 5.

I claim:

The ornamental design for a combined light support and filter actuating accessory bracket for a photographic camera, substantially as shown.
